UNITED STATES PATENT OFFICE.

JOHN HAYS HAMMOND, JR., OF GLOUCESTER, MASSACHUSETTS.

TELESTEREOTYPY.

1,370,504.

Specification of Letters Patent.

Patented Mar. 1, 1921.

Application filed November 30, 1912, Serial No. 734,270. Renewed July 23, 1920. Serial No. 398,543.

To all whom it may concern:

Be it known that I, JOHN HAYS HAMMOND, Jr., a citizen of the United States, residing at Gloucester, in the State of Massachusetts, have invented certain new and useful Improvements in Telestereotypy, of which the following is a specification.

My invention relates to tele-stereotypy, or the art of reproducing the forms and shapes of surfaces and solids at a distance, and it relates more particularly to systems for making reproductions of such forms and shapes at stations distant from the original, by means of electric transmission, either by wire or without wire connection.

Referring to the accompanying drawings:

Figure 1 shows, in diagrammatic form, a sending station and a receiving station connected by wire, and embodying one form of my system of tele-stereotypy.

Fig. 2 shows, diagrammatically, a sending station employing radio transmission for one form of my system of tele-stereotypy.

Fig. 3 shows, also diagrammatically, a corresponding radio receiving station for my system of tele-stereotypy.

In Fig. 1, Q is a body whose shape is to be reproduced at a distant station, P, P¹ and P² are rods or pins of any suitable form and material, which can move in the direction of their length under the control of the springs S, S¹ and S², respectively. The outer ends of these rods are in contact with the body Q and coincide with points on its surface. U, U¹ and U² are contact points attached to the rods P, P¹ and P² and the springs S, S¹ and S², respectively, and these points make contact with the electric resistances T, T¹ and T², respectively, the amount of resistance in each circuit depending upon the position of the rods P, P¹ and P². F is a high-speed commutator, with contact pieces K, K¹ and K² which make contact with the brushes J, J¹ and J², respectively, at certain periods in the rotation of commutator F, and which are all connected with the terminal Y, which is in contact with the brush I. K¹² is a contact piece which also makes contact with brush J at another period in the rotation of commutator F and is also connected with terminal Y. There are other contact pieces, not shown, on the commutator F, all con-

nected with the terminal Y, so that each brush J, J¹ and J² makes contact several times during one revolution of the commutator, but so that only one brush is in contact at a time. V is a battery or other source of current, and W is a choke coil. V and W are both connected, through the line wire X, with the distant receiving station. O is an electric motor which causes the commutator F to rotate, and which is also connected with the receiving station by means of the line wire X. E and E¹ are ground connections.

O¹ is an electric motor, at the receiving station, running in synchronism with motor O, and rotating high-speed commutator F¹ in synchronism with commutator F. K³, K⁴, K⁵ and K¹² are contact pieces, all connected with the terminal Y¹, which, in turn, is connected, through the brush I¹ and the choke coil W¹, with the line wire X to the sending station. The brushes J³, J⁴ and J⁵ make contact with the contact pieces K³, K⁴ and K⁵, respectively, and are in circuit with the electromagnets M, M¹ and M², respectively. There are other contact pieces, not shown, on the commutator F¹, all connected with the terminal Y¹, so that each brush J³, J⁴ and J⁵ makes contact several times during one revolution of the commutator, but so that only one brush is in contact at a time.

The electromagnets M, M¹ and M² when energized, attract the magnetic core pieces, n, n¹ and n², respectively, which are attached to the rods or pins N, N¹ and N², respectively. These rods will assume positions which depend upon the currents in the electromagnets M, M¹ and M², which currents will depend upon the positions of the rods P, P¹ and P² at the sending station. The outer ends of the rods N, N¹ and N² will therefore be caused to constitute points of a surface Q¹, which will correspond exactly with the surface of the body Q in contact with the rods P, P¹ and P². The springs Z, Z¹ and Z² are attached to the rods N, N¹ and N² and tend to operate against the attraction of the electromagnets M, M¹ and M², respectively, and restore the rods N, N¹ and N² to their original positions when this attraction ceases. E² is a ground connection to complete the circuit to the sending station. G is an alternating-current generator which supplies 110

current to the synchronous motors O^1 and O , connection being made with O by means of the line wire X and the ground connections E^3 and E^1 . The choke coil W and W^1 prevent this alternating current from passing through the battery V , the commutators F and F^1 and the rest of the apparatus. D^1 and D^2 are condensers which allow this alternating current to pass through the motors O and O^1 , but which prevent the direct current, from the battery V , from passing through the motors O and O^1 and the generator G and escaping to earth at E^1 and E^3 .

When motors O and O^1 are in operation, the commutators F and F^1 rotate synchronously, so that resistance T and electromagnet M , resistance T^1 and electromagnet M^1 , and resistance T^2 and electromagnet M^2 are successively connected in an electric circuit including the commutators F and F^1 , the battery V and the line wire X . The speed of the commutators F and F^1 is so high, and the electrical and mechanical inertia of the rods N , N^1 and N^2 and the core pieces n , n^1 and n^2 are so great that the interruptions in the circuits will be unnoticeable at the rods N , N^1 and N^2 .

If a surface such as the lower side of the body Q be placed upon rods P , P^1 and P^2 , the latter will be depressed against the upward pressure of the springs S , S^1 and S^2 , the amount of depression depending upon the shape of Q . The resistances T , T^1 and T^2 will therefore be varied correspondingly, and so will the currents in the electromagnets M , M^1 and M^2 . The cores and rods n , N , n^1 , N^1 , and n^2 , N^2 will therefore assume positions corresponding to those of the rods P , P^1 and P^2 , and if a flexible surface Q^1 be attached to the ends of these rods, it will take a shape like that of the lower side of body Q . The more rods that are used, the closer will be the similarity of the surfaces Q and Q^1 , and as many rods may be used as is convenient and practical. It is evident that not only one surface of the body Q can be reproduced at the receiving station, but that all its surfaces can be so reproduced by arranging rods at its sides and at its top in suitable positions and suitably connected, and having corresponding rods at the receiving station actuated by electromagnets or otherwise. The surfaces at the receiving station, such as Q^1 , may be made of any suitable material, and may constitute molds in which a solid body can be formed which will be identical with the body at the sending station. It is also evident that raised letters, reliefs and other objects can be reproduced at a distant receiving station in a similar manner.

In Fig. 2, H is a source of continuous high-frequency oscillations operatively related to the resonant antenna A by means of

the coupling coils L and L^1 . The antenna A is connected to ground at E^4 through the variable elements T^3 , T^4 and T^5 , successively; by the high-speed commutator F^2 , the purpose of the variable elements T^3 , T^4 , T^5 being to fix the amplitude of the waves radiated during their period of action, their magnitude depending upon the position of the rods or pins P^3 , P^4 and P^5 .

Q^2 is a body whose lower surface is in contact with the ends of the rods P^3 , P^4 and P^5 and depresses them against the action of the springs S^3 , S^4 and S^5 , respectively. Attached to the rods and springs are contact points U^3 , U^4 and U^5 , which make contact with the elements T^3 , T^4 and T^5 . The elements T^3 , T^4 and T^5 are connected, respectively, with the brushes J^6 , J^7 and J^8 , which make contact with the contact pieces K^6 , K^7 and K^8 at certain periods of the revolution of the commutator F^2 . Contact piece K^{14} also makes contact with the brush J^6 at a certain period of the revolution of commutator F^2 . There are other contact pieces, not shown, on the commutator F^2 , so that each brush J^6 , J^7 and J^8 makes contact several times during one revolution of the commutator, but so that only one brush is in contact at a time. These contact pieces are all connected with the terminal Y^2 which is in contact with the brush I^2 , the latter being grounded at E^4 . The synchronous motor O^2 operates the commutator F^2 .

In Fig. 3, B is a receiving antenna, grounded at E^5 and tuned to the wave length of sending antenna A by means of the inductance coil L^2 and the variable condenser C . The closed oscillation circuit L^3 C^1 , comprising the inductance coil L^3 and the variable condenser C^1 , is in resonance with the antenna circuit B L^2 C E^5 , and is inductively coupled to the latter by means of the coils L^2 and L^3 . The closed oscillatory circuit L^3 C^1 is arranged in a well known manner to act through a condenser D to control a rectifier R through which a unidirectional current is supplied to the controlled circuit containing the commutator F^3 , and electromagnets M^3 , M^4 and M^5 . The circuits containing the magnets M^3 , M^4 and M^5 , respectively, are tuned so that they will be most strongly energized for certain magnitudes of the elements T^3 , T^4 and T^5 . The arrangement may be such that when the rod P^3 , for instance, is in its lowest position, the electromagnet M^3 will be most strongly energized, and will cause the core piece n^3 and the rod N^3 to assume their lowest position.

In the art of radio transmission it is well known that in order to attain efficient tuning it is necessary to have circuits whose electrical oscillation is persistent and slowly damped. Therefore, in all cases where I have shown detectors it is to be understood

that I may employ such detecting devices as present the least ohmic resistance in a circuit.

The electric motor O^3 is caused to rotate 5 in synchronism with motor O^2 of the sending station, by any means well known to the art of radio transmission. This motor O^3 thus rotates the high-speed commutator F^3 in synchronism with commutator F^2 at the 10 sending station. K^9 , K^{10} , K^{11} and K^{15} are contact pieces on the commutator F^3 , the first three making contact, respectively, with the brushes J^9 , J^{10} and J^{11} , at certain periods 15 in the rotation of commutator F^3 , and contact piece K^{15} also making contact with brush J^9 at another period in the rotation of commutator F^3 . There are other contact pieces, not shown, on the commutator F^3 , so that each brush J^9 , J^{10} and J^{11} makes contact 20 several times during one revolution of the commutator, but so that only one brush is in contact at a time. These contact pieces are all connected with the terminal Y^3 , which makes contact with the brush I^3 , 25 which is connected with rectifier R . The brushes J^9 , J^{10} and J^{11} are in circuit, respectively, with the electromagnets M^3 , M^4 and M^5 , which are all connected with the rectifier R . The magnetic cores n^3 , n^4 and n^5 are 30 operatively related to the electromagnets M^3 , M^4 and M^5 , respectively, and are mechanically connected with the rods or pins N^3 , N^4 and N^5 , respectively. The cores n^3 , n^4 and n^5 will be more or less strongly attracted 35 by the electromagnets M^3 , M^4 and M^5 , and will thus cause the rods N^3 , N^4 and N^5 to assume various positions which will depend upon the positions of the rods P^3 , P^4 and P^5 at the sending station of Fig. 2. The 40 outer ends of the rods N^3 , N^4 and N^5 will therefore constitute points of a surface Q^3 which will correspond exactly with the surface of the body Q^2 in contact with the ends of the rods P^3 , P^4 and P^5 . The springs Z^3 , 45 Z^4 and Z^5 are attached to the rods N^3 , N^4 and N^5 , and tend to operate against the attraction of the electromagnets M^3 , M^4 and M^5 , respectively, and they restore the rods N^3 , N^4 and N^5 to their original positions when 50 this attraction ceases.

In a similar manner with Q^1 in Fig. 1, Q^3 may be a flexible surface attached to the ends of rods N^3 , N^4 and N^5 , which will conform to the shape of the corresponding surface 55 at the sending station. The more elements like P^3 , P^4 and P^5 , and N^3 , N^4 and N^5 that are used, the closer will be the similarity of the surfaces at the sending and the receiving stations, and it is evident that not 60 only one surface of the body Q^2 can be reproduced at the receiving station, but that all its surface can be so reproduced, as already explained in connection with body 65 Q in the description of Fig. 1. The other remarks there made about the various appli-

cations and modifications of my system of tele-stereotypy apply to the modifications shown in Figs. 2 and 3, and in general I do not confine myself to the particular apparatus here shown, but various other changes 70 and modifications, within the skill of those versed in the art, may be made in the particular apparatus shown and described herein, without departing from the spirit of my invention, provided the means set forth in 75 the following claims be employed.

Having thus described my invention, I claim:—

1. A method for the transmission of forms through a distance which consists in automatically varying a plurality of adjustable mechanical elements at a sending station by bringing the same into contact with a primary surface, varying the amount of electric energy transmitted to a receiving station according to the movement of said elements, and successively controlling a plurality of independent elements at said receiving station by electric circuits successively energized by said modified electric 85 energy, so that said receiving elements shall cause the surface at the sending station to be reproduced at the receiving station.

2. A system for the transmission of forms through a distance comprising a sending 95 station provided with a plurality of independent mechanical elements adapted to have movement imparted thereto by contact with a primary surface, and a plurality of electric elements under the control of said mechanical elements, and a receiving station provided with a plurality of mechanical elements corresponding to the mechanical elements at the sending station and controlled by a plurality of electric elements 100 which are controlled by corresponding electric elements at the sending station, said mechanical receiving elements being adapted to contact with a secondary surface and modify the shape thereof.

3. A system for the transmission of forms through a distance comprising a sending station provided with a plurality of independently movable mechanical elements adapted to contact with and have their 115 movements controlled by the form of an independent body, and a plurality of electric elements under the control of said mechanical elements, and a receiving station comprising a corresponding number of mechanical elements, each of said elements being electrically controlled by its corresponding element at the sending station, so as to reproduce the position of its corresponding sending element, and adapted to engage 120 with a pliable surface so as to modify the shape thereof.

4. A system for the transmission of forms through a distance comprising a sending station and a receiving station in electric 125

- communication with each other, said sending station being provided with a plurality of independent mechanical elements whose positions can be independently fixed by contact with an independent body of the form intended to be transmitted, and a plurality of electric elements under the control of said mechanical elements, and a receiving station provided with a plurality of mechanical elements and a plurality of electrical elements which are controlled by the corresponding elements at the sending station, said mechanical receiving elements having their positions thereby fixed so as to reproduce the shape of the body at the sending station. 5
5. In a system for the transmission of forms through a distance, a sending station comprising a plurality of mechanical elements capable of independent adjustment by contact with an independent body, and a plurality of electric elements whose respective magnitudes are controlled by said mechanical elements. 10
6. In a system for the transmission and reception of radiant energy the combination with a sending station comprising a source of electrical oscillations of a given frequency, a transmission conductor associated therewith, and automatic means for successively varying said oscillations, of a receiving station comprising a receiving conductor tuned to said frequency and adapted to receive oscillations of radiant energy from said transmission conductor, a plurality of receiving devices and means for causing said receiving devices to coöperate successively with said receiving conductor. 15
7. In a system for the transmission and reception of radiant energy the combination with a sending station comprising a source of practically continuous electrical oscillations of a given frequency, a transmission conductor associated therewith, and automatic means coöperating with said conductor for successively varying said oscillations, of a receiving station comprising a receiving conductor tuned to said frequency adapted to receive oscillations of radiant energy from said transmission conductor, a plurality of receiving devices and means synchronized with said first mentioned means for causing said receiving devices to coöperate successively with said receiving conductor. 20
8. In a system for the transmission and reception of radiant energy, the combination with a sending station comprising a source of practically continuous electrical oscillations, a transmission conductor associated therewith, and automatic means for successively varying the amplitude of said oscillations, of a receiving station comprising a receiving conductor adapted to receive oscillations of radiant energy from said transmission conductor, a plurality of receiving devices and means synchronized with said first mentioned means for rendering said devices suc- 25
- first mentioned means for causing said receiving devices to coöperate successively with said receiving conductor. 30
9. In a system for the transmission and reception of radiant energy, the combination with a sending station comprising a source of practically continuous electrical oscillations of a given frequency, a transmission conductor associated therewith, and automatic means for successively and intermittently varying the amplitude of said oscillations, of a receiving station comprising a receiving conductor tuned to said frequency adapted to receive oscillations of radiant energy from said transmission conductor, a plurality of receiving devices and means synchronized with said first mentioned means for causing said receiving devices to coöperate successively and intermittently with said receiving conductor. 35
10. In a system for the transmission and reception of radiant energy, the combination with a transmission station comprising means for transmitting electrical oscillations, and means for successively varying the amplitude of said oscillations, of a receiving station comprising a plurality of receiving devices and means synchronized with said second mentioned means for rendering said devices successively effective. 40
11. In a system for the transmission and reception of radiant energy, the combination with a sending station comprising means for transmitting radiant impulses, and means for successively varying said impulses at a predetermined frequency, of a receiving station comprising a plurality of receiving devices, and means synchronized with said second mentioned means for rendering said devices successively effective. 45
12. In a system for the transmission and reception of radiant energy, the combination with a sending station comprising means for transmitting radiant impulses, a plurality of elements, and means for rendering said elements successively effective to modify said impulses at a predetermined frequency, of a receiving station comprising a plurality of receiving devices, and means synchronized with said second mentioned means for rendering said devices successively effective. 50
13. In a system for the transmission and reception of electric energy, the combination with a sending station comprising a source of electrical oscillations, a sending conductor associated with said source, a plurality of resistances, and means for automatically connecting said resistances successively in series with said conductor to vary the amplitude of said oscillations, of a receiving station comprising a receiving conductor, a plurality of receiving devices, and means synchronized with said first mentioned means for rendering said devices suc- 55

cessively effective to coöperate with said receiving conductor.

14. In a system for the transmission of electric energy, the combination with a source of electric oscillations, of a conductor associated with said source, a plurality of resistances, and means for automatically connecting said resistances successively in series with said conductor to successively 10 vary the amplitude of said oscillations.

15. In a system for the transmission of forms through a distance, a sending station comprising a plurality of movable elements capable of independent adjustment by contact with an independent body the form of which is intended to be transmitted, and a plurality of electric elements arranged to have their effective magnitudes controlled by said movable elements respectively.

16. The combination with means for generating electrical oscillations of a given frequency, of means automatically operative to effect successive variations in the amplitude of said oscillations, and means for receiving said oscillations including a plurality of devices responsive successively to said variations.

17. The combination with means for generating electrical oscillations of a given frequency, of means automatically operative to effect successive variations in the amplitude of said oscillations, and means for receiving said oscillations including movable distributing means synchronized with said variations and a plurality of receiving devices controlled by said distributing means and responsive successively and respectively to said variations.

18. The combination with means for generating electrical oscillations of a given frequency, of means automatically operative to effect variations periodically and at a predetermined rate in the amplitude of said oscillations, and means for receiving said oscillations including a plurality of devices responsive successively to said variations.

19. The combination with means for generating electrical oscillations of a given frequency, of means automatically operative to effect successive variations in the amplitude of said oscillations, and means for receiving said oscillations including movable distributing means synchronized with said variations and a plurality of receiving devices controlled by said distributing means and responsive successively and respectively to said variations.

20. The combination with means for generating electroradiant oscillations of a given frequency, of means automatically operative to effect successive variations in the amplitude of said oscillations, receiving means tuned to said frequency for receiving said oscillations, distributing means operatively 60 connected to said receiving means and syn-

chronized with said second mentioned means, and a plurality of devices successively controlled by said distributing means.

21. In a system for the transmission of forms through a distance, a sending station comprising a plurality of movable elements arranged to be separately adjusted by contact with an independent body the form of which is intended to be transmitted, a plurality of electric elements arranged to have 70 their effective magnitudes controlled by said movable elements respectively, and means for rendering said electrical elements successively effective to control the transmission of energy from said station.

22. In a system for the transmission of forms through a distance, a sending station comprising a plurality of movable elements capable of being independently adjusted by contact with an independent body the form of which is intended to be transmitted, a plurality of electric elements arranged to have their effective magnitudes controlled by said movable elements respectively, means for transmitting radiant energy, and means for rendering said elements successively effective to control said energy transmission means.

23. In a system for the transmission of forms through a distance, a sending station comprising a plurality of movable elements capable of being independently adjusted by contact with an independent body the form of which is intended to be transmitted, a plurality of electric elements arranged to 95 have their effective magnitudes controlled by said movable elements respectively, means for transmitting electroradiant energy, and means for rendering said elements successively effective to control said transmission means.

24. In a system for the transmission of forms through a distance, a sending station comprising a plurality of movable elements arranged to be separately adjusted by contact with an independent body the form of which is intended to be transmitted, a plurality of electric elements arranged to have 110 their effective magnitudes controlled by said movable elements respectively, means for rendering said electrical elements successively effective to control the transmission of energy from said station, and a receiving station including a plurality of separately movable elements arranged to be moved as a result of and in accordance with the movements of said first mentioned elements respectively.

25. In a system for the transmission of forms through a distance, a sending station comprising a plurality of movable elements capable of being independently adjusted by contact with an independent body the form of which is intended to be transmitted, a plurality of electric elements arranged to 125

have their effective magnitudes controlled by said movable elements respectively, means for transmitting radiant energy, means for rendering said elements successively effective to control said energy transmission means, and a receiving station including a plurality of separately movable elements arranged to be moved as a result of and in accordance with the movements of said first mentioned elements respectively.

26. In a system for the transmission of forms through a distance, a sending station comprising a plurality of movable elements capable of being independently adjusted by contact with an independent body the form of which is intended to be transmitted, a plurality of electric elements arranged to

have their effective magnitudes controlled by said movable elements respectively, means for transmitting electroradiant energy, means for rendering said elements successively effective to control said transmission means, and a receiving station including a plurality of separately movable elements arranged to be moved as a result of and in accordance with the movements of said first mentioned elements respectively. 20 25

This specification signed and witnessed this 7 day of November, A. D. 1912.
